UNITED STATES PATENT OFFICE.

ROBERT M. HUGHES, OF OXFORD, PENNSYLVANIA, ASSIGNOR TO HIM-
SELF, J. A. BLAKE, AND H. WOOD.

IMPROVEMENT IN COUPLING-HEADS FOR RAILROAD CARS.

Specification forming part of Letters Patent No. 37,587, dated February 24, 1863.

To all whom it may concern:

Be it known that I, ROBERT M. HUGHES, of Oxford, Chester county, Pennsylvania, have invented certain improvements in Coupling-Heads for Railroad-Cars; and I do hereby declare the following to be a full, clear, and exact description of the same, reference being had to the accompanying drawings, and to the letters of reference marked thereon.

My invention consists of certain improvements, fully described hereinafter, in what are known as the "coupling" or "bumper heads" of railway-cars, the object of my said improvement being, first, the protection of the coupling-links against loss by negligence or theft; secondly, the prevention of delay when a coupling-link is broken or so far damaged as to be unsafe; and thirdly the attainment of ready means of coupling and uncoupling railway-cars.

In order to enable others skilled in the art to make and use my invention, I will now proceed to describe its construction and operation.

On reference to the accompanying drawings, which form a part of this specification, Figure 1 represents the coupling-heads of two adjacent cars a short distance apart from each other; Fig. 2, the same as Fig. 1, showing the heads as coupled together; and Fig. 3 a sectional plan of Fig. 1.

Similar letters refer to similar parts throughout the several views.

A and A' represent the coupling-heads of two adjacent cars, each head having a hollow stem, a, which is firmly secured to the frame of the car. In the upper portion of each head is an oblong opening, b, which communicates with the horizontal opening c, and in this oblong opening b is a catch-lever, B, the latter being hung to the pin d, which passes through the head A. This pin is so situated in respect to the catch-lever, and the latter is of such a form, that by its own gravity it has a tendency to retain the position illustrated in the drawings, its lower end resting on the bottom of the horizontal opening c of the head A, a projecting lip, e, however, affording a convenient handle by which the catch-lever can be elevated from the position illustrated. The lower portion of each head is cut away to the width of the opening c, and as far from the outer end of the head as the line x. (See Fig. 3.) In cutting this

portion away, however, a central hook-formed projection, i, remains, and to this projection is connected the link D, one end of this link taking its place at the bottom of the curved recess m. A pin, n, is driven diagonally through the lower portion of the head in such a position as to cross the curved recess m, and, being there permanently secured, prevents the escape of the link, which may in fact be considered a movable portion of the head, the part of the latter, which has been heretofore alluded to as being cut away, permitting the link to hang down loosely or to be elevated at pleasure.

It will be seen that the entrance to the horizontal opening c is beveled both at the sides and the top, and that the end of the hook-formed projection i is rounded so that the link of one of the coupling-heads can readily find its way to its proper destination in the horizontal opening c of the adjacent head when the two cars meet.

It should be understood that, although I have alluded in my above description to one head only, both of the coupling-heads A and A', as well as all their appliances, are precisely alike.

In coupling together two cars with my improvements attached, the link D of the head of either car may be elevated so that when the two cars approach each other the elevated link may pass into the opening c of the opposite head, and, striking the catch-lever B, elevate the latter until the end of the link has passed so far into the opening that the lever can fall by its own gravity or by the aid of a spring, if desired, after which the cars are securely coupled together.

If the link hung to the coupling-head of one car should be accidentally broken or so far damaged as to be unfit for coupling purposes, the link hung to the head of the adjacent car is always at hand for effecting the desired coupling, and the delay incurred in searching for a substitute for a broken link when ordinary coupling devices are used is obviated.

In addition to this advantage of my improvement there is that of the link being permanently hung to the coupling-head, the importance of which feature will be thoroughly understood by those familiar with the management of railroads, the loss of detachable

links and pins, which are liable to be mislaid or stolen, being a source of constant expense and annoyance to railroad companies.

By my improvement every facility is afforded for a ready coupling and uncoupling of the cars without resorting to the removal of parts, both the catch-lever and link being permanent attachments.

I do not desire to claim, broadly, the use of the catch lever B, in connection with a coupling-head; but

I claim as my invention and desire to secure by Letters Patent—

1. The combination of the coupling head A and link D, when the latter is permanently connected to the former by the hooked pro-

jection i and pin m, or their equivalents, and when the head is so formed in respect to the link as to allow the same to be raised or lowered, the whole being constructed substantially as and for the purpose herein set forth.

2. In combination with the said coupling-head A and link D, the catch-lever B, hung to the head and arranged and operating substantially as and for the purpose specified.

In testimony whereof I have signed my name to this specification in the presence of two subscribing witnesses.

R. M. HUGHES.
